(**) Term: **14 Years**

(57) **CLAIM**

(21) Appl. No.: **29/166,751**

The ornamental design for a computer generated image for
a display panel or screen, as shown and described.

(22) Filed: **Sep. 5, 2002**

DESCRIPTION

(51) **LOC (7) Cl. 14-02**
(52) **U.S. Cl. D14/486**
(58) **Field of Search** D14/485-95; D18/24-33;
D19/6; D20/11; D21/324-33; 345/700-26,
764-862

The single FIGURE is a front view of a computer generated
image for a display panel or screen showing my design.
The broken line drawing of a display panel or screen is for
illustrative purposes only and forms no part of the claimed
design.
